(57) **CLAIM**

The ornamental design for a string bed for a tennis racquet, as shown and described.

DESCRIPTION

FIG. 1 is a front view showing a first embodiment of our design, the rear view being a mirror image thereof;

FIG. 2 is a top perspective view of the first design embodiment, the bottom perspective view being a mirror image thereof;

FIG. 3 is a front view showing a second embodiment of our design, the rear view being a mirror image thereof;

FIG. 4 is a top perspective view of the second design embodiment, the bottom perspective view being a mirror image thereof;

FIG. 5 is a front view showing a third embodiment of our design, the rear view being a mirror image thereof; and,

FIG. 6 is a top perspective view of the third design embodiment, the bottom perspective view being a minor image thereof.

The broken line showing is included for the purpose of illustrating and forms no part of the claimed design.
